ADJUSTABLE NEEDLE GUARD FOR SEWING MACHINES

William Jacobson and Francis E. Quest,
New York, N. Y.

Application December 13, 1935, Serial No. 54,167

2 Claims. (Cl. 112—261)

Our present invention relates to the guarding of sewing machine needles, and more particularly to an improved and adjustable needle guard for a sewing machine of the power driven type.

5 Needle guards, devised for power driven sewing machines especially adapted for use in factories, should not only be exceedingly simple in construction and involve a minimum of attention on the part of the operator, but also must interfere in no way with the working efficiency of the operator. The needle guard member itself should be exceedingly simple in construction, and readily attached to any type of sewing machine. It often happens that an operator is transferred 10 from a sewing machine having a presser foot of one size to another machine whose presser foot has a different dimension. A needle guard should be constructed so that it lends itself to ready transfer between machines, and thus 15 causes minimum interference with the operator.

The novel features which we believe to be characteristic of our invention is set forth in particularity in the appended claims; the invention itself, however, as to both its construction 20 and method of operation will best be understood by reference to the following description taken in connection with the drawing in which we have indicated diagrammatically a construction whereby our invention may be carried into effect.

30 In the drawing:—

Fig. 1 is a perspective view of the presser foot of a sewing machine embodying the present invention.

Fig. 2 is a view of the presser foot and attached guard taken on the reverse side of Fig. 1.

Fig. 3 is a sectional view on line 3—3 of Fig. 2 looking in the direction of the arrows,

Fig. 4 is a perspective view of one portion of the needle guard,

40 Fig. 5 is a perspective view of the remaining portion of the needle guard.

Referring now to the accompanying drawing, wherein like reference characters in the different figures designate similar mechanical elements, the numeral 2 designates the presser bar which normally depends from the head of the sewing machine. The numeral 3 denotes the needle bar; and there is secured upon the lower end of the presser bar 2, by means of the screw 4, a presser foot 5 of the usual and well known construction. A needle 6 is attached to the needle bar 3 by means of the screw 7 in the customary fashion.

55 The presser foot itself is of a type well known to those skilled in the art, and comprises the

usual toe 5' which is provided with the spaced fingers 8 and 9. Each of these two fingers have their free ends curved upwardly in order that the work material may readily move under them. The finger 8 is provided with a ledge 9, and it will be understood that the toe 5' is pivotally secured to the upright portion of the presser foot 5. As those skilled in the art are well aware, the presser toe 5' is normally spring-pressed, as by spring 10, in a downward direction at the rear side of the toe portion. This type of self-adjustable presser foot is so well known in the art that it needs no further description.

The needle guard is designated by the numeral 11, and as shown in Fig. 4 it is substantially L-shaped in configuration. The horizontal portion 11 thereof includes a recess 12 which conforms in outline to the contour of the rear of the presser foot. The vertical portion of the guard is provided with a right angle bend whereby there is furnished the extension 13.

The extension 13 has a length substantially equal to the length of the vertical section of the needle guard, and its width is sufficient to enable it to provide a grip on the rear face of the presser foot 5. An aperture 14 is provided at substantially the mid-section of the extension 13; and a second aperture, of greater size than aperture 14, is denoted by the numeral 15, and is provided close to the upper edge of the vertical section of the needle guard. The vertical section of the needle guard has a complementary member 16, shown in detail in Fig. 5, and it will be observed that this member 16 has a length substantially equal to the length of the vertical section of the needle guard, and has an extension 17 provided by bending an edge of member 16 at right angles.

An aperture 18 is provided close to the upper edge of member 16, and this aperture 18 is located so that it will register with the aperture 15, when the needle guard and its complementary member 16 are in operative position. As shown in Fig. 3, the threaded shank 19 of screw 4 is arranged to pass through the apertures 15 and 18 in order to secure the needle guard to the presser foot 5. A threaded shank 20 is provided substantially at the mid-section of the unbent vertical edge of member 16, and a knurled head 21 is provided with a threaded axial bore to receive the threaded shank 20. The shank 20 is arranged to pass through the aperture 14 in the extension 13 of the needle guard; and from Fig. 3 it will be observed that proper rotation of the knurled head 21 will serve to clamp the extensions 13 and 17 to the front

and rear faces of the presser foot 5. In this way the upper section of the needle guard is provided with an adjustable clamping action.

The length of the horizontal portion 11' of the guard 10' is such that it substantially covers the entire length of the finger 8. As shown in Figs. 1 and 3 the horizontal portion 11' of the needle guard has a height such that the finger of the operator which is customarily placed adjacent finger 8 is completely guarded against any accidental piercing by needle 6. Furthermore, the height of this horizontal portion 11' is made such that when the needle 6 is at its uppermost position, the point thereof will be sufficiently below the horizontal 15 edge 11'', see Fig. 2, of the horizontal portion 11' to render the guard entirely fool-proof.

The inner face of the lower edge 22 of the needle guard is in contact with the vertical edge of the toe 5', and this protects substantially the 20 entire outer edge of the finger 8. The horizontal section 11' of the needle guard is provided with a stamped out portion 30 in order to render the needle guard light without in any way impairing its accident preventing properties. It is to be 25 noted that the edge 11'' serves as a guide for the thread when the operator desires to thread the needle without necessitating in any manner the removal of the finger guarding barrier. Merely by way of example, it is pointed out that in the 30 uppermost position of needle 6, as shown in Fig. 2, the threading eye is about $\frac{1}{16}$ of an inch above the edge 11''.

It will now be seen that the needle guard of the present invention comprises but a single plate, 35 and the upper section of the plate having a complementary member 16 so as to positively grip the front and rear faces of the presser foot 5. Furthermore, there has been provided adjusting means for varying the spacing between the 40 extensions 17 and 13 so that presser feet of different widths may be readily gripped by the needle guard. In other words, it will be observed that the vertical section of the needle guard virtually provides an adjustable clamping channel member 45 which is variable in width.

In actual usage it is very simple for the operator to use the device of the present invention. Assuming that the needle guard is in operative position, as shown in Fig. 1, and the operator 50 desires to remove the needle guard to another presser foot which is of a different machine; it is only necessary for the operative to first rotate the screw head 4 to remove the shank 19. The shank 19 being removed from apertures 15 and 55 18, the needle guard with its complementary member 16 screwed to it, is then removed. It is not necessary to disturb the setting of head 21 since the gripping parallel edges 13 and 17 of the adjustable channeled clamp can be slipped off the front and rear faces of the presser foot 5 with 60 ease. When the needle guard is taken to the next machine, it is only necessary to pass the shank 19 of the securing screw 4 through the apertures 15 and 18, and then tighten the screw 4 to 65 secure the needle guard to its new presser foot 5.

In making this new attachment if the width of the presser foot 5 is greater than the spacing between gripping edges 13 and 17, it is only necessary to rotate the knurled head 21 to a sufficient 70 point such that the edge 13 may be moved with respect to edge 17, and thus provide a new spacing which is equal to the width of the next presser foot

5. With this new spacing the head 21 is rotated in the opposite direction to tightly clamp the front and rear faces of the presser foot between the clamping edges 13 and 17. Of course the material of the guard may be brass or steel; it is 5 pointed out that its particular composition is immaterial to its functioning in the present invention, except that it be rigid in nature.

It will be obvious that the present invention, due to its simplicity and positive protecting function, as well as its ready adjustment to presser feet of different widths, is of great value to owners of factories with power driven sewing machines, in that it reduces the number of accidents caused by piercing of operators' fingers, and 15 hence effects a material saving in those States where workmen's compensation laws are in effect.

While we have indicated and described a construction for carrying our invention into effect, it will be apparent to one skilled in the art, that our 20 invention is by no means limited to the particular construction shown and described, but that many modifications may be made without departing from the scope of our invention, as set forth in the 25 appended claims.

What we claim is:

1. A needle guard for a sewing machine comprising a substantially L-shaped plate formed from a single piece of flat metallic material, said plate having the vertical edge of the vertical section thereof bent at an angle to the plane of the plate, a second plate adapted to contact the vertical section of said needle guard plate, said second plate having an edge thereof bent at an angle such as to provide a clamping channel 35 between the bent edges of the two plates, said second plate and the vertical section of the first plate being provided with registering apertures, and means disposed in the apertures adapted to secure said plates to the sewing machine presser 40 foot, a threaded element extending from the unbent vertical edge of the second plate, and an aperture in the bent edge of the first plate for receiving said threaded element, and means for adjustably engaging said threaded element where- 45 by the width of said channel may be varied at will.

2. A needle guard for a sewing machine, said needle guard being formed from a single plate of rigid material and being shaped to provide a 50 horizontal section and a vertical section, the horizontal section being provided with an opening to minimize the weight of the needle guard, the horizontal section extending along the side of the sewing machine presserfoot, when in operative 55 position, and being high enough to function as a complete barrier to an operator's finger, the vertical section being provided with an aperture to receive the means for securing the needle guard to the presser foot, and a vertical edge of said 60 vertical section being bent at right angles to the plane of the needle guard plate, said bent edge being provided with an aperture, a second plate, of substantially the same configuration as the vertical section of the needle guard plate, said 65 second plate having an aperture registering with the first named aperture of said needle guard plate, and a threaded element projecting from the second plate and adapted to register with the aperture in the bent edge of said first plate.
